METHOD FOR RECOVERING PROPANE AND
HEAVIER HYDROCARBONS

Francis W. Winn, Woodbury, and Lester R. Stefens, Pitman, N. J., assignors to Socony-Vacuum Oil Company, Incorporated, a corporation of New York

Application July 28, 1950, Serial No. 176,286

3 Claims. (Cl. 196—11)

1

This invention relates to a process for recovering liquids and gases from petroleum fractions. In particular, the method described herein is concerned with an improved procedure for recovering propane and heavier hydrocarbons from a petroleum fraction boiling within the range of gasoline by effective demethanization and deethanization thereof.

The conventional processes heretofore employed for effecting removal of methane and ethane from petroleum fractions containing hydrocarbons boiling within the range of gasoline have involved feeding the stock to be treated into a bubble tower maintained at a temperature such that the methane and ethane tend to pass overhead while the higher boiling hydrocarbons are obtained as a bottoms product. In practice, however, such processes, due to lack of ideal contacting conditions, have invariably resulted in the passage overhead of considerable amounts of propane, butane, and heavier hydrocarbons along with the methane and ethane whose removal was desired. Subsequent recovery of propane and heavier hydrocarbons from the overhead has generally entailed passage of the same through an absorber-stripper system. Such operation, however, is relatively expensive. Very often, it has accordingly been the practice to forego high recovery of propane and heavier hydrocarbon components from the overhead with the result that substantial losses of these materials were incurred.

It is an object of the present invention to reduce the aforementioned losses by providing a method for recovering substantially all of the propane, as well as heavier hydrocarbons, from a petroleum fraction containing hydrocarbons boiling within the range of gasoline. It is a further object of this invention to accomplish the removal of methane and ethane from such fractions without simultaneously removing propane and heavier hydrocarbons therefrom. A still further important object is the provision of an improved process for economically effecting deethanization and demethanization of a petroleum fraction with minimum accompanying loss of propane, butane, and higher hydrocarbons.

These and other objects which will be apparent to those skilled in the art are attained in accordance with the procedure of the instant invention wherein petroleum fractions containing hydrocarbons boiling within the range of gasoline are essentially demethanized and deethanized by passage of the same through a combination of two fractionating columns, one of which is operated at a high pressure and the other of which is operated at a considerably lower pressure.

In the accompanying drawing, the figure

2

shown is a schematic view of the apparatus employed in the instant process.

Referring more particularly to the drawing, numeral 10 designates a conduit for the introduction of hydrocarbon feed, which is generally a mixture of hydrocarbons boiling within the range of gasoline. The gasoline fraction so introduced is suitably the effluent of a reformer operating at high pressure. The vaporous hydrocarbon charge is quenched in vessel 11, and thereafter further cooled and condensed in reboiler service by passage through pipe 12, through reboilers 13 and 14, and then via pipes 15 and 16 through an additional cooler 17. The cooled charge is then recycled, as shown, to the original feed line 10 serving to at least partially cool the incoming hydrocarbon charge. The cooled feed finally passes from vessel 11 through conduit 18 and is totally condensed and water-cooled upon passage through cooler 19. The cold feed then flows through pipe 20, condenser 21, and pipe 22 into reflux accumulator 23 and thereafter passes from said accumulator through conduits 24 and 25 and pump 26, the latter serving to force the cold feed through pipe 27 and into the upper portion of fractionating column 28. This column is operated essentially as a high pressure stripper and it is important for present operation that the feed be introduced into the column at the point of maximum pressure and minimum temperature in order to effectively reduce the overhead loss of propane and other desired heavy components. This is accomplished in accordance with the instant method by introducing the feed into the high pressure column via the reflux condenser or alternatively, as discussed hereinbelow, to the top plate of the condenser.

The overhead gas from high pressure column 28 passes through outlet pipe 29 into line 30 carrying the cold liquid feed. This combined stream is conducted through condenser 21 and pipe 22 into accumulator 23. The overhead gas flows from accumulator 23 through conduits 33 and 34 to turbine 32 wherein it is expanded to fuel line pressure (about 30 p. s. i.). The gas becomes cold during expansion and flows from turbine 32 through pipes 33 and 34 through reflux condenser 21 serving to cool the same. The overhead of ethane and lighter gases then passes through pipe 35 and may be used as a fuel gas or for any other desired purpose.

Since the loss of propane and heavier component is related to the temperature of the reflux condenser, it is desirable to minimize the loss by maintaining the condenser at a temperature as low as consistent with commercial operation. The auto-refrigeration obtained through expansion of overhead gases as described above may, if desirable, be augmented by additional refrigeration. On the other hand, if hydrate for-

mation is considered a problem, the temperature could be maintained at a point of about 70° F. or higher, at which no hydrate formation would be encountered.

The bottoms product from high pressure column 28 passes through outlet conduit 36 to the top tray of fractionating column 37 which is operated at an appreciably lower pressure than column 28. Deethanization of the feed charge is completed in this low pressure column. The overhead vapor issuing from this column consists of ethane saturated with heavier components and is conducted to the bottom of high pressure column 28 in order to recover the propane and butane contained therein and to provide heat necessary for the stripping operation accomplished in the high pressure column. The recycling from column 37 to column 28 is effected by passage of the overhead through conduit 38 through cooler 39 and then into reflux accumulator 40. The recycle vapor passes from accumulator 40 through pipe 41 into a turbo-compressor 42 driven by overhead gas from column 28, which gas is conducted from the reflux accumulator 23 of said column through conduit 31 and turbine 32. The gas introduced into turbo-compressor 42 from accumulator 40 becomes heated during compression thereof and the resulting hot gas under pressure is led through conduit 43 into the bottom of column 28.

Reflux from accumulator 40 is returned to column 37 via conduit 44, the flow being aided by pump 45. The bottoms from low pressure column 37 are removed through outlet pipe 46. The bottoms so obtained contain tar, gasoline, butane, propane, and less than 1% of ethane (based on propane content). This material thus substantially free of ethane and lighter components may thereafter be fractionated into the various products by conventional means.

It is to be realized that temperatures and pressures employed in various parts of the foregoing system are of extreme importance in accomplishing the stated objects of this invention. The term "convergence pressure" as used herein is the maximum pressure, for any specified temperature, at which any separation of the components of the particular hydrocarbon mixture can be accomplished by distillation. As this pressure is approached, the vapor-liquid equilibrium ratios of all the components converge toward unity, all relative volatilities of the components approach unity, and the difficulty of separation increases. At the convergence pressure, the equilibrium ratios are all equal to unity; relative volatility likewise is unity for all components, and separating is impossible. The feed charge, as pointed out hereinabove, is preferably, but not necessarily, the effluent of a high pressure reformer. In such instances, the pressure of the feed, and consequently the pressure at which column 28 is operated, will correspond substantially to the full outlet pressure of the reformer. Under the usual conditions of the instant process, the minimum pressure at which column 28 is operated is about 200 pounds per square inch less than the convergence pressure of the bottoms product of column 37. As a general rule, the pressure at which column 28 is operated is within the approximate range 300 to 3000 pounds per square inch and preferably between about 500 and about 2000 pounds per square inch. Particularly efficient operation is accomplished in the vicinity of about 1000 pounds per square inch. The temperature of the feed, assuming it to be the effluent of a high pressure

reformer, is generally about 1000° F. This elevated temperature is considerably lowered by quenching and cooling of the feed to an extent such that the temperature thereof after passing through cooler 19 is 100° F. or less. The temperature of the feed introduced into column 28 is generally further reduced upon passing through condenser 21. Indeed, the losses of propane, butane, and heavier components by passage of these gases overhead from column 28 are relatively small if the reflux condenser temperature of this column is maintained below about 100° F. The losses at varying temperatures for a 10,000 barrel per day reformer gas plant are set forth in the table below:

Reflux Condenser Temp., °F.	Loss (Barrels per day)			Loss, Percent of Component	
	Propane	Butane	C5+	Propane	Butane
100	120	42	15	8.1	3.0
60	58	18	6	3.8	1.3
40	32	9	3	2.1	0.7

From the above, it will be apparent that the temperature at which the feed is introduced into the high pressure fractionating column generally should not exceed about 100° F. Preferably, this temperature should be 60° F. or less in order to minimize the loss of desired propane and heavier components.

It is further important in practice of the present invention that the feed be introduced into the high pressure column at the point of lowest temperature. In accordance with conventional fractionating tower operation, feed charged thereto is subjected to a stripping action by raising its temperature as it flows down the column and the vapors thus stripped have their temperature lowered as they rise in the column. The point at which feed is introduced into the column of the present invention is the top of column where the temperature is at a minimum. This is accomplished, in accordance with the instant procedure, by introduction of the feed to the reflux condenser of the high pressure column or, alternatively, the feed, after being cooled, may be introduced to the top plate of the condenser by way of conduit 47.

The bottoms temperature of the second column is maintained high enough to insure boiling of the bottoms product at the existent pressure and to reject all ethane and lower boiling components as overhead. This bottoms temperature generally is within the range 300 to 450° F., depending upon the particular pressure conditions existent in the column. This pressure, in turn, is established at a level such that critical conditions of the desired bottoms product will not be encountered in the bottom of the column. Ordinarily, the pressure at which this second column is operated should be 500 pounds per square inch or less. The pressure, however, should not be too low or otherwise auxiliary power will be required for operation of the turbo-compressor. The minimum feasible pressure for effective operation of this column is generally about 200 pounds per square inch. It is further desirable in operating the instantly described system that the pressure differential between the high pressure column 28 and the low pressure column 37 be at least about 200 pounds per square inch and suitably about 600 pounds per square inch. Thus, it is preferred to operate the upper high pressure fractionating col-

umn at about 1000 pounds per square inch and the low pressure column at about a pressure of about 400 pounds per square inch.

With the foregoing combination of fractionating columns, effective demethanization of a gasoline fraction is carried out while reducing to a minimum the losses of propane and heavier hydrocarbon components heretofore encountered. Thus, in accordance with the present invention, substantially all of the propane, as well as heavier components, are recovered from a petroleum fraction containing hydrocarbons boiling within the range of gasoline while accomplishing almost complete rejection of methane and ethane from said fraction.

It is to be understood that the above description is merely illustrative of preferred embodiments of the invention of which many variations may be made within the scope of the following claims by those skilled in the art without departing from the spirit thereof.

We claim:

1. A method for removing methane and ethane from a petroleum fraction containing hydrocarbons boiling within the range of gasoline, which comprises introducing said petroleum fraction into a high pressure fractionating zone at the point of minimum temperature therein, passing the overhead gas emitted from said high pressure zone to a condensing zone wherein high boiling components of said overhead gas are liquefied, recycling said liquefied components as reflux to said high pressure fractionating zone, expanding remaining gas with resultant cooling thereof, flowing the resulting cooled gas in indirect heat exchange with the aforementioned condensing zone serving to cool the same, passing the liquid bottoms product of said high pressure fractionating zone into a second fractionating zone maintained at a pressure of at least 200 pounds per square inch less than the pressure of said high pressure fractionating zone, the minimum pressure of said second fractionating zone in turn being about 200 pounds per square inch, withdrawing the vaporous effluent of said second fractionating zone, cooling the same to liquefy the high boiling components thereof, recycling resulting liquid as reflux to said second fractionating zone, compressing remaining vapor in a turbo-compressor driven by the aforesaid overhead gas from said high pressure zone, conducting the resulting gas, heated as a result of compression, to the bottom of said high pressure fractionating zone, withdrawing methane and ethane as overhead from said high pressure fractionating zone and withdrawing heavier hydrocarbons as bottoms product from said second fractionating zone.

2. A method for removing methane and ethane from a petroleum fraction containing hydrocarbons boiling within the range of gasoline, which comprises introducing said petroleum fraction at a temperature not exceeding about 100° F. into a high pressure fractionating zone at the point of minimum temperature therein, said zone being maintained at a pressure between about 300 and about 3000 pounds per square inch, passing the overhead gas emitted from said high pressure zone to a condensing zone wherein high boiling components of said overhead gas are liquefied, recycling said liquefied components as reflux to said high pressure fractionating zone, expanding remaining gas with resultant cooling thereof, flowing the resulting cooled gas in indirect heat exchange with the aforementioned condensing

zone serving to cool the same, passing the liquid bottoms product of said high pressure fractionating zone into a second fractionating zone maintained at a pressure of at least 200 pounds per square inch less than the aforementioned high pressure zone, the pressure of said second fractionating zone being between about 200 and about 500 pounds per square inch, withdrawing the vaporous effluent of said second fractionating zone, cooling the same to liquefy high boiling components thereof, recycling resulting liquid as reflux to said second fractionating zone, compressing remaining vapor by the pressure action of the aforesaid overhead gas from said high pressure zone, conducting the resulting gas, heated as a result of compression, to the bottom of said high pressure fractionating zone, withdrawing methane and ethane as overhead from said high pressure fractionating zone and withdrawing heavier hydrocarbons as bottoms product from said second fractionating zone.

3. A method for removing methane and ethane from a petroleum fraction containing hydrocarbons boiling within a range of gasoline, which comprises introducing said petroleum fraction into a high pressure fractionating zone at a temperature not exceeding 100° F. at the point of minimum temperature therein, said zone being maintained at a pressure between about 500 and about 2000 pounds per square inch, passing the overhead gas emitted from said high pressure zone to a condensing zone wherein high boiling components of said overhead gas are liquefied, recycling said liquefied components as reflux to said high pressure fractionating zone, expanding remaining gas with resultant cooling thereof, flowing the resulting cooled gas in indirect heat exchange with the aforementioned condensing zone serving to cool the same, passing the liquid bottoms product of said high pressure fractionating zone into a second fractionating zone operated at a pressure between about 200 and about 500 pounds per square inch and maintained at a temperature sufficient to reject ethane and lower boiling components, the minimum pressure differential between said high pressure fractionating zone and said second fractionating zone being between about 200 pounds per square inch, withdrawing the vaporous effluent of said second fractionating zone, cooling the same to liquefy high boiling components thereof, recycling resulting liquid as reflux to said second fractionating zone, compressing remaining vapor by the pressure action of the aforesaid overhead gas from said high pressure zone, conducting the resulting compressed gas, heated as a result of compression, to the bottom of said high pressure fractionating zone, withdrawing methane and ethane as overhead from said high pressure fractionating zone and withdrawing heavier hydrocarbons as bottoms product from said second fractionating zone.
